[57] ABSTRACT

A distributor for internal combustion engine having a rotor of a non-conducting material mounted on a grounded distributor shaft. A metal point support plate is adjustably supported on the rotor and has a plurality of rotary contact points mounted thereon. Advantageously a stationary contact is mounted on the distributor for successive engagement by the rotary contact points, the stationary point having an arcuate contact surface for rolling engagement by the rotary contact points. Metallic fasteners releasably hold the rotor on the distributor shaft and ground the plate to the shaft. The distributor has a condenser, a stationary point, and a rotor with the rotary contact points which are releasably mounted in the distributor for convenient manual replacement.

**DISTRIBUTOR FOR INTERNAL COMBUSTION ENGINE
WITH IMPROVED ADJUSTABLE ROTOR CONTACT
ASSEMBLY**

This invention relates to a distributor for internal combustion engines, and more particularly to an improved distributor having rotary points cooperating with a spring biased stationary contact point and parts that may be readily replaced without tools. This invention is an improvement on my previous invention disclosed in U.S. Pat. No. 3,062,928 entitled "Distributor for Internal Combustion Engine" which was issued on Nov. 6, 1962.

It is an object of the present invention to provide an improved distributor for internal combustion engines with points that remain cooler and wear longer than conventional distributor points.

It is another object of this invention to provide such a distributor with points and a condenser that can be readily replaced manually without tools.

It has now been found that the foregoing objects and other advantages can be obtained in a distributor for internal combustion engines that includes a rotor of non-conducting material mounted on a grounded distributor shaft. A metal point support plate is adjustably mounted on the rotor and has a plurality of rotary contact points mounted thereon. Advantageously a stationary contact point is mounted on the distributor for successive engagement by the rotary contact points, the stationary point having an arcuate contact surface for rolling engagement by the rotary contact points. Metallic fasteners releasably hold the rotor on the distributor shaft and ground the plate to the shaft. The distributor has a condenser, a stationary point, and a rotor with the rotary contact points which are releasably mounted in the distributor for convenient manual replacement.

The point support plate has a plurality of arms which carry the rotary contact points which are formed by wheel-shaped contacts rotatably mounted thereon. The stationary point is mounted on a spring which biases the stationary point into engagement with the rotary contact points.

The rotor has an annular member of non-conducting material on which the support plate is adjustably mounted. The metallic fasteners are in the form of a pair of resilient clips fixed on the rotor on one end and biased against the distributor shaft on the other end to releasably retain the rotor on the distributor shaft. The clips also provide an electrical circuit between the point support plate and the grounded distributor shaft.

The distributor is adapted so that the points and the condenser may be readily replaced manually without the use of tools. The metallic fasteners releasably hold the rotor on the distributor shaft so that it can be manually slipped off the top of the shaft. A spring member is mounted in the distributor and the stationary contact point has a slot for slideably receiving the spring member for releasability and supporting the stationary contact point. The distributor also has a condenser which is supported by a spring clip which allows the condenser to be manually replaced. In addition, the electrical conduit between the condenser and the ignition coil is provided with a socket which may be manually slipped on and off a lug connection on the condenser for ready replacement of this part without tools.

Various other objects and advantages of this invention will be apparent from the following detailed description, the claims, and the drawings appended hereto wherein:

FIG. 1 is an exploded view of the distributor for an internal combustion engine of this invention with the replaceable parts shown aligned with their mounting means. The distributor cap is not shown for clarity of illustration;

FIG. 2 is a top view of the distributor of this invention with the replaceable parts in operating position;

FIG. 3 is a cross sectional view of the distributor of FIG. 2;

FIG. 4 is a side view of the distributor of FIG. 2;

FIG. 5 is a cross sectional view taken along lines 5-5 of FIG. 4.

Referring now in detail to the drawings, there is illustrated a distributor housing 10 of conventional construction having rotatable grounded distributor shaft 12 disposed centrally therein and driven by an internal combustion engine in the usual manner. As illustrated in FIG. 3, the shaft 12 extends upwardly through a suitable aperture in an internal support plate 14 mounted in the housing 10. For clarity of illustration, the conventional distributor cap connected to the six spark plugs of an internal combustion engine is not shown.

10 The upper portion of the distributor shaft 12 has a head portion 20 configured to receive a rotor 22 advantageously adapted to be releasably disposed thereon. As illustrated in FIG. 3, the rotor has an internal cylindrical chamber 23 which receives the shaft head 20. A key way in the head 20 receives a key 23a formed in the chamber 23 whereby the rotor 22 rotates with the shaft 12.

The rotor 20 is made of conventional non-conducting material and has a conventional rigid arm portion 24 which 20 supports the usual flexible metal contact lever 25 having a rounded contact point 26 positioned to extend into the conventional distributor cap (not shown) for completing an electrical circuit in the usual manner between the ignition coil and the spark plugs of an internal combustion engine.

25 The rotor 22 has an annular member 30 of insulating material rigidly secured thereon to form a support for a metal point plate 32. The annular member 30 may be integrally formed as a part of the rotor 22 or it may be of separate construction in the form of a donut shaped ring which fits snugly

30 on the rotor 22 as illustrated in FIG. 3. The annular member 30 illustrated in FIG. 3 is of separate construction and has been slipped on a conventional rotor in order to adapt the rotor for use in the manner disclosed herein. The point plate 32, as best seen in FIG. 5, is designed in the form of a six-point star like member having equally spaced radially extending arms 34 and an annular aperture in which the body of the rotor 22 is disposed.

35 A pair of oppositely disposed arcuate slots 35 are formed in the plate 32 in order to adjustably mount the plate 32 on the annular member 30. Conventional pairs of fasteners, in the form of nuts 36 and screws 37 which pass through the slots 35 and through suitable apertures in the annular member 30, hold the point support 32 in a desired fixed position. The fasteners may be released so that the position of the point plate 32 relative to the rotor 22 may be adjusted in order to advance or retard the distributor timing.

40 In order to releasably retain the rotor 22 on the shaft head 20 and to ground the metal point plate 32 to the distributor shaft 12, a pair of resilient metal clips 38 are fixed to the point plate 32 by the screws 37 in the manner illustrated in FIGS. 3 and 4. Each of the clips have downwardly and inwardly extending flanges 39 which are biased into contact with the distributor shaft 12 in order to releasably retain the rotor 22 thereon and to ground the point support plate 32 thereto. For replacement or repair, the rotor 22 can be readily removed from the shaft 12, as illustrated in FIG. 1, by manually pulling the rotor 22 upwardly against the bias of the clips 38.

45 Advantageously pairs of rotatable contact points 40 are mounted on each of the arms 34 of the point support plate 32. Each of the rotary points 40 consist of a pair of wheel-like contacts 42 mounted on each side of an arm 34 and secured thereon by a copper pin or rivet 44 which passes through an aperture in the point support plate 32 so that the contact points 40 are rotatable thereon. Thus each rotary point 40 has four wheel-like contacts 42 forming rotary contact points of the embodiment illustrated in the drawings. However, only one wheel-like contact is required, the four wheels being used

50 in the embodiment disclosed to increase the contact area. A pair of copper washers 45 are disposed between each of the pairs of wheel-like contacts 42 and the point support plate 32. The copper rivets 44 and the copper washers 45 act to complete the circuit between wheel-like contacts 40 and the point plate 32.

A single contact 50 is mounted in the housing 10 in a position so as to be successively engaged by the rotary contact points 40. A vertical spring stem 52 supports the contact point 50 in position where the spring stem 52 biases the contact point 50 into engagement with rotary points 40 as these members are successively moved into contact therewith by the rotary distributor shaft 12. The contact point 50, as illustrated in FIGS. 1 and 2, is generally rectangular and has an arcuate contact surface 51 adopted to allow the rotary contact points 40 to come into engagement therewith and roll over the surface thereof to establish an electrical connection between these parts. This construction and operation has the desirable result of allowing the contact points to remain cooler and wear longer.

A suitable slot 53 is provided in the contact point 50 to receive the spring stem 52 in order to mount the contact point thereon. As illustrated in FIG. 1, the contact point 50 may be readily removed from the spring stem 52 by manually sliding the point 50 upwardly and off the stem for maintenance or replacement.

The spring stem 52 is mounted on the housing 10 by means of an insulating terminal 54 which is supported by and extends through the housing 10 as illustrated in FIG. 3. The terminal 54 has a conducting screw 56 supported internally therein and which extends into the interior of the housing 10. In order to support the spring stem 52, the screw 56 is disposed in an aperture in the spring stem 52 so that this part is held firmly between the terminal 54 and a spring stop 58 mounted on the outer end of the screw 56. The outer end of the screw is connected in a conventional manner to the high tension ignition coil of the internal combustion engine by means of the insulated conductor 60.

A grounded condenser 62, electrically connected to the ignition circuit of the internal combustion engine, is releasably mounted on the support plate 14 by means of a spring clip 64. Resilient flanges 66 and 68 of the clip 64 are configured to be biased into engagement with the cylindrical condenser 62 to hold it in place on the support plate 14. As illustrated in FIG. 1, the condenser 62 is mounted so that it may be manually removed from the spring clip 64 for replacement. In this connection the condenser 62 has a lug 70 extending therefrom for engagement with a mating conduit socket 72 which slides on the lug 70 to form a snug fit. When it is desired to replace the condenser 62, the socket 72 may be manually slipped off the lug 70. The lug 70 is attached on one end of a conduit 74 which has its opposite end electrically connected to the screw 56 of the terminal 54 to provide a conventional ignition circuit including the usual condenser 62.

Accordingly, as described in detail above, the condenser 62, the contact point 50 and the rotor 22 with the point plate 32 and the rotary points 40 may be readily removed manually from the distributor housing 10 without the use of tools and in addition it will be obvious to one skilled in the art, a conventional distributor may be readily adapted in the manner of this invention. Thus, these parts may be replaced in an inexpensive manner that does not require the services of an experienced mechanic. In addition, by removing the fasteners in the form of nuts 36 and screws 37, a new point plate 32 with fresh rotary points 40 may be placed on the rotor 22 so that this part may be reused. For this purpose a mark 76 is provided on the annular member 30 for alignment with the mark 78 on the point plate 32 to insure proper relative positioning of these

parts.

It will be understood that the foregoing description with the details of exemplary structure is not to be construed in any way to limit the invention, but that modifications may be made thereto without departing from the scope of the invention as set forth in the following claims.

Having thus described my invention I claim:

1. A distributor for an internal combustion engine including a rotor of non-conducting material mounted on a grounded distributor shaft, a metal point support plate adjustably mounted on said rotor, a plurality of rotary contact points mounted on said plate, a stationary point mounted on said distributor for successive engagement by said rotary contact points, said stationary point having an arcuate contact surface for rolling engagement by said rotary contact points, and metallic fastening means releasably holding said rotor on said distributor shaft and grounding said plate to said shaft.
2. The distributor of claim 1 wherein said point support plate has a plurality of arms and wherein said rotary contact points are formed by wheel-shaped contacts rotatably mounted on said arms.
3. The distributor of claim 2 wherein said stationary point is mounted on a spring biasing said stationary point into an engagement with said rotary contact points.
4. The distributor of claim 3 wherein said rotor has an annular member of non-conducting material, said point support plate being adjustably mounted on said annular member.
5. The distributor of claim 4 wherein said metallic fastening means includes a pair of resilient clips fixed on said rotor on one end and biased against said distributor shaft on the other end to releasably retain the said rotor on said distributor shaft, said clips providing an electrical circuit between said plate and said grounded distributor shaft.
6. A distributor for an internal combustion engine wherein the points and condenser can be readily replaced manually without the use of tools including a rotor of non-conducting material releasably mounted on a grounded distributor shaft, a metal point support plate adjustably mounted on said rotor, metallic fastening means releasably holding said rotor on said distributor shaft and grounding said plate to said shaft, a plurality of rotary contact points mounted on said plate, a stationary contact point mounted on said distributor for successive engagement by said rotor contact points, said stationary point having an arcuate contact surface for rolling engagement by said rotary contact points, a spring member mounted in said distributor, said stationary point having slot means for slideably receiving said spring member for releasably supporting said stationary point.
7. The distributor of claim 6 wherein said point support plate has a plurality of arms and wherein said rotary contact points are formed by wheel-shaped contacts rotatably mounted on said arms.
8. The distributor of claim 7 wherein said metallic fastening means includes a pair of resilient clips fixed on said rotor on one end and biased against said distributor shaft on the other end in order to releasably hold the said rotor on said distributor shaft, said clips providing an electrical circuit between said plate and said grounded distributor shaft.
9. The distributor of claim 8 wherein a condenser is releasably mounted in said distributor by a spring clip and wherein said condenser is connected to the ignition coil by a manually releasable lug and socket joint.
